CONCRETE PILE

Shigeru Watanabe and Koji Nunokawa, Tokyo, Japan,
assignors to Nippon Concrete Industries Company, Ltd.,
Tokyo, Japan

Filed July 9, 1970, Ser. No. 23,886

Term of patent 14 years

Int. Cl. D25—01

U.S. Cl. D13—1

FIG.1

FIG.2

FIG.3

FIG.4

FIG.5

FIG.6

FIG.7

FIG.8

FIG. 1 is a front elevation and a rear elevation of a concrete pile showing our new design;

FIG. 2 is a side elevation as seen from the left of FIG. 1;

FIG. 3 is a side elevation as seen from the right of FIG. 1;

FIG. 4 is a bottom plan view thereof;

FIG. 5 is a top plan view thereof;

FIG. 6 is a cross sectional plan view taken along the line 6—6 of FIG. 1;

FIG. 7 is a cross sectional elevation taken along the line 7—7 of FIG. 4; and

FIG. 8 is a perspective view thereof.

The characteristic features of the instant invention include the novel combination of a column having four perpendicular planar surfaces, a planar top surface, a cylindrical annulus extending the length of the column,

having an axis the same as the column, a bottom having three outer bevels angularly disposed to three interior tapered planar surfaces joining the expanded annular cylinder.

We claim:

The ornamental design for a concrete pile, as shown and described.
